UNITED STATES PATENT OFFICE.

JOHN W. KELLER, OF STANHOPE, NEW JERSEY.

ATTACHMENT FOR SLIDING DOORS.

1,372,514.

Specification of Letters Patent. Patented Mar. 22, 1921.

Application filed May 7, 1919. Serial No. 295,287.

To all whom it may concern:

Be it known that I, JOHN W. KELLER, a citizen of the United States, residing at Stanhope, in the county of Sussex and State of New Jersey, have invented new and useful Improvements in Attachments for Sliding Doors, of which the following is a specification.

The purpose of the invention is to provide a device for use in connection with sliding doors, particularly such doors as are used on freight cars, the invention being particularly designed to prevent the door being pried away from the opening at the rear end (or end remote from the fastener) and near the bottom. In freight cars particularly, unauthorized persons may gain access to the car without breaking the seal by simply prying the door away from the car at that edge remote from the locking device. By this means they are enabled to rob the car of a portion of its contents without the fact becoming known until the seal is broken or the locking device removed if the door is provided with a locking device.

While the invention is designed for particular use with car doors it can be made to serve a useful purpose with any character of sliding door, since it will effectively prevent the door being pried away from the door frame or opening at the bottom and at the end remote from that at which the fastener is carried.

The invention is illustrated and described in a specific embodiment to which, however, it is not to be restricted. The right is reserved to make such changes or alterations as the actual reduction to practice may suggest, in so far as such changes or alterations are compatible in spirit with the annexed claims.

The same numerals of reference designate the same parts throughout the several figures of the drawings, wherein:

Figure 1 is a view in side elevation of a portion of a freight car and the door provided therefor.

Fig. 2 is an elevational view of the inside of the door which is equipped with the invention.

Fig. 3 is an enlarged detail sectional view through the door post of the car and through the rear end of the door.

Fig. 4 is an enlarged detail sectional view on the line 4-4 of Fig. 2.

Fig. 5 is a section on the line 5-5 of Fig. 1.

Referring to the drawings, there is shown a portion of a freight car 1, this portion being in the vicinity of the door opening 2, which is closed, as is usual, by the door 2, the latter being supported by hangers 3 which run in a track 4 of the usual construction. The usual feet 5 are attached on the side of the car below the level of the bottom edge of the door and are designed to overhang the bottom edge and engage the face of the door to prevent its being moved outwardly at the lower edge. When the door is in closed position, however, these feet 5 are not sufficient to prevent the door being pried away from the door opening at the rear end and it is to successfully prevent this that the present invention is designed.

In the construction of freight cars, a post 6 is positioned at either side of the door opening, and through the post standing at the rear end of the door, which is the end remote from the hasp or fastener, there is passed a bolt 7, this bolt passing through the siding 8 as well as through the post and receiving on its inner end which is interior to the car the nut 9 and washer 10. The outer end, or that end which projects beyond the siding 8 is formed with a head 11 and at a specific distance back of this head, the bolt is bored to receive a pin 12 which may be in character of a straight pin but is preferably a cotter pin. The tightening of the nut 9 will serve to draw the bolt 7 through the post 6 until the cotter pin is in abutting relation to the siding 8. This leaves the head 11 spaced from the siding. The headed end of the bolt 7 is designed to carry a roller 13 and this roller is bored so that it may turn freely on the bolt and is counterbored to provide a space for the head 11, so that the latter will lie flush with the outside of the roller, the inside standing in abutting position to the pin. There is, however, enough play between the roller and the pin to permit the roller's turning freely.

On the inner face of the door 2 there is provided a track for engagement by the roller 13 and this track is composed of two oppositely disposed Z rails 14 which are bolted to the siding of the door, as indicated at 15, so that the narrow flanges 16 may lie within the plane of the frame 17 of the door. These

- two flanges 16 are spaced apart to provide clearance space for the bolt 7 and they and the web portions of the Z rails provide a track in which the roller 13 may run. The 5 roller 13 being carried by the post 6 at the rear of the door opening, as the door is closed, the track composed of the rails 14 moves along the roller and its flanges 16 engage behind the roller, the pin 12 spacing the roller far enough from the siding 8 to 10 permit these flanges passing behind the roller. When the door has been brought to closed position, the roller stands at the rear end of the track composed of the rails 14 and the rear end of the door, therefore, may 15 not be pried away from the door opening, which would be a possible performance were not the track and its attendant roller provided.
- 20 Just as effectively as it accomplishes its design with respect to car doors, so can the improved device accomplish the same design with reference to other kinds of sliding doors where the possibility of prying the door away 25 from the door opening exists.

The invention having been described, what is claimed as new and useful is:

1. The combination with a sliding door, of a roller mounted at one side of the door opening, and a track carried by the door on the inner face thereof, the said roller moving in the track, the track being provided with inturned flanges engaging behind the roller for the useful purpose specified.
2. The combination with a sliding door, of a roller, a bolt on one end of which the roller is rotatably mounted, a track carried on the inner face of the door in which track the roller moves, the track being provided with inturned flanges engaging behind the roller, and means carried by the bolt in abutting relation to the roller and serving as means for spacing the latter from the frame of the door opening to permit the said flanges passing behind the roller, as and for the purpose herein specified.

In testimony whereof he affixes his signature.

JOHN W. KELLER.
